UNITED STATES PATENT OFFICE.

SIEGMUND CHIGER, OF BERLIN, GERMANY.

DEVICE FOR COUPLING THE COIN-EJECTORS IN CHANGE-GIVING APPARATUS.

1,078,331.

Specification of Letters Patent. Patented Nov. 11, 1913.

Application filed February 18, 1913. Serial No. 749,170.

To all whom it may concern:

Be it known that I, SIEGMUND CHIGER, a subject of the Emperor of Austria-Hungary, residing at 65 Kurfürstendamm, Berlin, Germany, have invented new and useful Improvements in Devices for Coupling the Coin-Ejectors in Change-Giving Apparatus, of which the following is a specification.

The present invention relates to improvements in devices for coupling coin-ejectors of change-giving apparatus to their operating means, and is particularly applicable to that type of change-giving apparatus in which the coin-ejectors are actuated by a push bar or other pressure device to which they are coupled by the intermediary of coupling members which are moved into the coupling position by the aid of levers actuated by the cams or projections of corresponding drums or disks.

The main object of the invention is to prevent those coin-ejectors which from any cause whatever do not contain coins from being coupled to the driving means, and to retain these ejectors in their inoperative position in which position the ejectors prevent, by means of certain auxiliary devices connected therewith, the levers operating the coupling members from being brought into action.

According to the invention the levers which operate the coupling members are mounted upon other levers which may properly be called supporting levers in such a manner as to move, when actuated by the corresponding cam disks or drums, the supporting levers into the path of oscillating frames or members provided with slots and adapted to assume two positions. In the one position the slotted frame or member serves as an abutment against which the supporting lever rests, whereby the corresponding actuating lever is kept in a position ready for operating the coupling member under the influence of the corresponding disk or drum, while in the other position, the supporting lever enters into a slot of the oscillating member and thus renders the corresponding actuating lever inoperative.

In the accompanying drawings one construction of a device embodying the features of the invention is shown by way of example.

Figure 1 is a top view showing a detail, Fig. 2 is a section on line A—A of Fig. 1, Figs. 3, 4, 5 and 6 are diagrammatical views

showing the parts in various positions, Figs. 7, 8 and 9 illustrate details.

The coin-ejecting slide 1 (Fig. 1) is provided with an opening or recess 2 which serves for receiving a coin of a certain sort. In the construction shown it is assumed that the opening contains a 1 pfennig coin. The coin-ejecting slide 1 is connected to a rod 3 by means of which it is advanced for the purpose of ejecting a coin. The coin ejector or the rod fixed thereto may be coupled by means of a coupling member 5 to a transverse ejector bar 4 which is adapted to be moved in the horizontal direction after the coin ejector 3 has been coupled thereto. The means for moving the push bar 4 do not form part of the invention and may be of any known kind. This coupling member 5 may be brought into the coupling position by means of a projection 6 of a rotatable disk or drum 7, which is loosely mounted upon a shaft 8 and is provided with lateral pins or projections 9. By the side of the disk 7 and fixed thereto is arranged upon the shaft 8 a gear 10 which meshes with a toothed rack 11 which is operated in a manner similar to the rack 14¹ described in my copending application Serial No. 749,171. By moving the toothed rack 11 the disk 7 is moved from the zero position into an intermediate position in which the projection 6 is ready to act upon a device by which the coupling member is moved into the coupling position. Fig. 3 shows the projection 6 in the zero position, this position being indicated by full lines, and in the above mentioned intermediate position which is indicated by dotted lines.

The coupling member 5 is mounted upon the transverse push bar 4 and is adapted to slide relatively to the bar in the vertical direction, the bar engaging into suitable recesses 12 of the coupling member. The coupling member 5 is actuated from above by a lever 14 pivoted at 13. This lever is actuated by a lever 15 which will hereinafter be called the actuating lever and which is pivotally mounted at 17 upon another lever 16 which will hereinafter be called the supporting lever. The lever 16 is pivoted at 18. By turning the lever 16 the free end of the actuating lever 15 may be moved into the path of the projection 6 or withdrawn out of the reach of the projection 6. For this purpose the lever 16 is provided with an extension 19 with which co-operates the

arm 20 of a lever 22 adapted to oscillate upon the fixed shaft 21 and provided with an arm 23. To this arm is connected a rod 24 which is mounted upon a link K and is adapted to be actuated by means of a cam disk 7 operated by a crank y. By turning the crank y the rod 24 is caused to move the lever 22 into the position shown in Fig. 3 or to return same into the initial position shown in Figs. 4, 5 and 6.

In the position shown in Fig. 3, the lever 22 holds the lever 15 outside the path of the projection 6, while in the position shown in Figs. 4 to 6, the lever 15 is not influenced by the lever 22, but may be or is projected into the path of the projection 6.

In order to couple the coupling member 5 with the corresponding ejector rod 3, the corresponding disk 7 has to be moved from the intermediate position shown in Fig. 4 into the position shown in Fig. 6. This is effected by a driving pawl 25 which cooperates with one of the lateral pins 9 and is moved in the direction of the arrow in Fig. 4. The pawl 25 is pivotally mounted upon a slide or rod 26 and is acted upon by a spring 27 in such a manner that when the rod is moved backward, by means of the handle n, that is, in the direction opposite to that indicated by the arrow, the pawl may slide past the pin of the disk which at this time is locked. The pawl 25 corresponds to the pawl 5 of my copending application Serial No. 749,171 hereinbefore referred to, and is only adapted to turn the disk 7 by one tenth of a revolution, that is, from the intermediate position into the operative position.

In order to prevent the lever 15 which is to be rendered operative by the projection 6 from moving together with its supporting lever 16 about the shaft 18, provision is made to retain the supporting levers 16 in a suitable position. For this purpose the lever 16 is provided with a nose 28. When the lever 15 is pressed down the projection or nose 28 presses against the portion 29 of an oscillating member 30 which is provided with a slot or recess 31 and a cam arm 32. The arm 32 rests in the normal position of the oscillating member 30 against a fixed stop 33 as shown in Figs. 4 and 6.

In order to return the coupling member 5 from the coupling position shown in Fig. 6 into the initial position shown in Figs. 3 to 5, there is provided underneath the rod 3 and within a stationary casing 34 a pusher 36 which is slidably mounted and is actuated by a spring 35. The pusher is provided with a projection 37 and a recess or opening 38. In the position of rest, the projection 37 of the pusher takes into a recess or notch 39 of the rod 3. In order to hold the pusher 36 and the coupling member 5 in the operative positions (Fig. 6) even

after the action of the projection 6 has ceased, there is provided a locking bolt 40 which is slidably mounted in the bar 4 and takes into the recess 38 of the pusher. When the bar 4 is advanced in the direction of the arrow in Fig. 4, the locking pawl is withdrawn from the pusher 36, but the pusher cannot lift the coupling member. When the bar 4 is moved in the opposite direction, the coupling member 5 slides with its lower inclined portion up upon the pusher and raises the lever 14 and the lever 15.

The coupling member should be moved into the coupling position shown in Fig. 6 only when the opening 2 of the ejector 1 contains a coin as shown in Fig. 1. If the opening 2 is empty the slide or coin-ejector 1 should be moved into the inoperative position shown in Fig. 5. In order to move the ejector into the inoperative position there is provided a reciprocating rod 41 which acts upon the ejector rod 3 by means of a conical member 42. This conical member takes into a recess 43 of the rod 3. When the rod 41 is moved to the right, the conical member 42 has the tendency to move the ejector 1 and the rod 3 into the position shown in Fig. 5, in which position as above mentioned, the coupling member 5 cannot be brought into engagement with the rod 3. This case occurs when the ejector slide 1 is empty. If the ejector slide contains the proper coin to be ejected, it is prevented from moving into the inoperative position by a stationary pin 45 which projects upwardly through a slot 44 of the slide 1 (Figs. 1, 2 and 9) and retains the slide in its operative position through the intermediary of the coin.

In order to prevent the operating disk from damaging the parts 14, 15, normally operated thereby when the ejector 1 has been brought into the inoperative position (Fig. 5) in which the coupling member 5 cannot enter the rod 3, the following device is provided: The rod 3 is provided with an arm 46 which carries a two-armed lever 48, 49, which under the influence of a weight 47 has the tendency to assume the position shown in Fig. 4. If desired a spring might be provided instead of the weight 47. The lever 16 is provided at its tail end with an extension 50 having an inclined cam surface 51. When the rod 3 is moved in the direction opposite to that indicated by the arrow, into the inoperative position shown in Fig. 5, the arm 48 is brought into close proximity to the inclined cam surface 51. When afterward the disk is moved from the intermediate position into the position shown in Fig. 5, the lever 16 is oscillated in the upward direction. During this upward movement the lever 16 moves the arm 49 to the right, shown in Fig. 5, and the latter moves 130

the lever 30 into such a position that the part 29 of the lever is moved out of the path of the projection 28, the latter projection entering the slot or recess 31. The rod 3 is 5 returned to the position shown in Fig. 4 by the projection 52 of the rod 41. The movement of the rod 3 by the rod 41 is limited by the projection 37 of the pusher which takes into a recess 39 of the rod 3.

10 The lever 30 is provided with a lateral pin 53 which engages into a slot 54 of a link pivoted to the lever 22 at 55. This arrangement serves for moving the part 30 into the inoperative position shown in Fig. 15 3, by the movement of the lever 22. In the set position the lever 15 is moved out of the reach of the projection 6, and the disk is, therefore, moved into the intermediate position shown in Fig. 4 without actuating the 20 lever 15.

The rod 41 may be actuated by means of a disk 57 mounted upon a shaft 56 and provided with a cam groove 58 into which engages a pin 59 of the rod 41. The end 60 of 25 the rod 41 is forked and engages the shaft 56 so that it serves as a guide for the rod which is constrained to perform a rectilinear movement. The shaft 56 is provided with a crank α whereby it can be rotated.

30 I claim:—

1. A device for coupling coin-ejectors for change-giving apparatus comprising in combination a push-bar, a coin-ejector, a coupling member for connecting said ejector to said push-bar, a supporting lever, a coupling lever mounted on said supporting lever, means for causing said coupling lever to actuate said coupling member, and means for moving said ejector into inoperative 40 position and for preventing said coupling lever from being brought into action, substantially as set forth.

2. A device for coupling coin-ejectors for change-giving apparatus comprising in 45 combination a push-bar, a coin-ejector, a coupling member for connecting said ejector to said push-bar, a pivotally mounted supporting lever, a coupling lever mounted on said supporting lever, a pivotally mounted

50 member which serves to retain the coupling lever in operative position and an actuating member adapted to engage said coupling lever and to cause same to actuate said coupling member, substantially as set forth.

55 3. A device for coupling coin-ejectors for change-giving apparatus comprising in combination a push-bar, a coin-ejector, a coupling member for connecting said ejector to said push-bar, a pivotally mounted supporting lever, a coupling lever mounted thereon, a pivotally mounted member which serves in one position to retain said coupling lever in operative position, means for moving the coin-ejector backward when same is

empty, and means comprising a double-armed lever mounted on said ejector and arranged to move said pivotally mounted member into a position which renders the coupling lever inoperative, substantially as 70 set forth.

4. A device for coupling coin-ejectors for change-giving apparatus comprising in combination a coin-ejector means for moving said coin-ejector into the discharge position, a coupling member for connecting said ejector to said actuating means, a pivotally mounted supporting lever, a coupling lever mounted thereon, adapted to actuate said coupling member and an oscillating frame adapted to assume two positions, one position serving to retain coupling lever in operative position and the other to allow of said lever being moved out of operative position, substantially as set forth. 75 80 85

5. A device for coupling coin-ejectors for change-giving apparatus comprising in combination a push-bar, a coin-ejector, a coupling member for connecting said ejector to said push-bar, a pivotally mounted supporting lever, a coupling lever mounted on said supporting lever, a pivotally mounted member which serves to retain said coupling lever in operative position, a slot or recess in said pivotally mounted member, 90 means for giving a backward movement to the ejector when same is empty, and a lever mounted on said ejector and adapted on said backward movement to cause said slot in said pivotally mounted member to be moved into the path of said coupling lever, substantially as set forth. 95 100

6. A device for coupling coin-ejectors for change-giving apparatus comprising in combination a push-bar, a coin-ejector, a coupling member for connecting said ejector to said push-bar, a pivotally mounted supporting lever, a coupling lever mounted thereon and adapted to actuate said coupling member, a rotary disk, a projection thereon adapted to actuate said coupling lever, and means for withdrawing the said coupling lever out of the path of said projection, substantially as set forth. 105 110

7. A device for coupling coin-ejectors for change-giving apparatus comprising in combination a push-bar, a coin-ejector, a coupling member for connecting said ejector to said push-bar, a pivotally mounted supporting lever, a coupling lever mounted thereon and adapted to actuate said coupling member, a pivotally mounted member for retaining said coupling lever in operative position, a rotary disk, a projection thereon adapted to actuate said coupling lever, and means for withdrawing said pivotally mounted member from its retaining position and said coupling lever out of the path of said projection, substantially as set forth. 115 120 125

8. A device for coupling coin-ejectors for 130

change-giving apparatus comprising in combination a push-bar, a coin-ejector, a coupling member for connecting said ejector to said push-bar, a pivotally mounted 5 supporting lever, a coupling lever mounted thereon and adapted to actuate said coupling member, a pivotally mounted member for retaining said coupling lever in operative position, a double-armed lever, a link 10 connecting one arm of said lever to said pivotally mounted member, and means for operating said double-armed lever to cause same to oscillate said supporting lever and withdraw said pivotally mounted member 15 out of its retaining position, substantially as set forth.

9. A device for coupling coin-ejectors for change-giving apparatus comprising in combination a push-bar, a coin-ejector, a recess 20 at the bottom of said ejector, a coupling member adapted to slide in said push-bar, a pivoted lever arranged above said coupling member, a second lever pivotally mounted on a supporting lever for actuating the first 25 lever, a pusher slidably mounted in the push-bar, and a projection on said pusher adapted to take into the bottom recess of said ejector, substantially as set forth.

10. A device for coupling coin-ejectors 30 for change-giving apparatus comprising in combination, a push-bar, a coin-ejector, a recess at the top end and at the bottom of said ejector, a pusher slidably mounted in the push-bar, a projection on said pusher adapted 35 to take into the bottom recess of said ejector, a coupling member adapted to slide in said push-bar and to abut against said pusher, and means for causing said coupling member to engage with the top recess in said 40 ejector and to withdraw said projection from engagement with the bottom recess, substantially as set forth.

11. A device for coupling coin-ejectors for change-giving apparatus comprising in 45 combination, a push-bar, a coin-ejector, a recess at the top end and at the bottom of said ejector, a pusher slidably mounted in the push-bar, a projection on said pusher adapted to take into the bottom recess of said

ejector, a coupling member adapted to slide 50 in said push-bar and to abut against said pusher, means for causing said coupling member to engage with the top recess in said ejector and to withdraw said projection on said pusher from engagement with the bottom recess, and means for locking said pusher in its withdrawn position, substantially as set forth. 55

12. A device for coupling coin-ejectors for change-giving apparatus comprising in 60 combination, a push-bar, a coin-ejector, a coupling member for connecting said ejector to said push-bar, a pivotally mounted supporting lever, a nose on said lever, an inclined cam surface on said lever, a coupling lever mounted on said lever adapted 65 to actuate said coupling member, a pivotally mounted member arranged in the path of said nose, a slot in said pivotally mounted member, means for giving said ejector a 70 backward movement when same is empty, and a double armed lever on said ejector adapted to engage on said backward movement with said inclined cam surface and to move said slot into the path of said nose, 75 substantially as set forth.

13. A device for coupling coin-ejectors for change-giving apparatus comprising in combination, a push-bar, a coin-ejector, a recess at the end of said ejector, a coupling 80 member for connecting said ejector to said push-bar, a pivotally mounted supporting lever, a coupling lever mounted on said supporting lever and adapted to actuate said supporting lever, a reciprocating rod, a 85 spring mounted member on said rod adapted to take into said recess, a rotary disk, a cam groove in said disk and a pin on said rod adapted to engage with said cam groove, 90 substantially as set forth.

In testimony whereof I have signed my name to this specification in the presence of two subscribing witnesses.
